UNITED STATES PATENT OFFICE.

HARRY C. ZIMMERMAN, OF WASHINGTON, DISTRICT OF COLUMBIA.

TOP CARRIAGE FOR GUNS.

Application filed August 25, 1924. Serial No. 734,061.

(GRANTED UNDER THE ACT OF MARCH 3, 1883; 22 STAT. L. 625.)

To all whom it may concern:

Be it known that I, HARRY C. ZIMMERMAN, a citizen of the United States, and a resident of Washington, District of Columbia, have invented an Improvement in Top Carriages for Guns, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a top carriage for guns.

In guns of small caliber which are especially designed to accompany infantry or for use in mountainous country, the various 20 elements of the gun must be susceptible of rapid dismantling and assembly for transportation by hand to permit of extreme inactivity and strategic employment.

A gun of this character, to be of maximum 25 usefulness, must be divisible into the fewest possible number of individual loads so that a majority of the gun crew may be reserved to carry ammunition or other matériel.

30 According to the present invention, the top carriage for supporting the gun on its cradle consists of a pair of spaced upright members affixed to the forward end of a split trail and hooking over the axle of the gun carriage. A spacer rod between the supports retains threaded hinged caps at either end which are held to the underside of the axle by a pair of locking devices which engage the hinged caps of the cradle 35 trunnions to securely lock the assembly. A continuous movement of the locking devices will consequently serve to lock the trails to the axle and the gun cradle to the top carriage thereby rendering possible a rapid mounting or dismounting of the gun.

To these and other ends, my invention 40 consists in the construction, arrangement, and combination of elements, described hereinafter and pointed out in the claims forming a part of this specification.

A practical embodiment of my invention 45 is illustrated in the accompanying drawings, in which,

Fig. 1 is a fragmentary view in side elevation of a gun carriage showing the manner of supporting the trail and cradle; 55

Fig. 2 is a detailed view in side elevation of the top carriage; and

Fig. 3 is a sectional view taken on the line 3-3 of Fig. 1, the trunnion and axle removed. 60

Referring to the drawings by numerals of reference:

A gun carriage consisting of wheels 10 connected by a partially threaded axle 11, 65 includes the usual cradle 12 and trails 13, both of which are supported in a top carriage 14.

The top carriage 14 comprises a pair of upright supports 15, which may be formed 70 integrally with or securable to the front of the trails 13.

The supports 15 are each formed at their forward end with a vertically extending rib 16 terminating in semi-circular bearings, 75 the lower bearing 17 adapted to fit over the axle 11 and the upper bearing 18 adapted to receive the trunnions 19 of the gun cradle 12.

The supports are spaced by means of a bar 20, positioned underneath the cradle and serving to hingedly carry threaded caps 21, which when moved into position with the lower bearing 17, hold the top carriage to the axle and enable the gun to be traversed 85 in the usual manner, by rotation of the axle.

The free end of the lower cap 21 pivotally carries a rod 22 on which is eccentrically pivoted a lever 23 receivable in the bifurcated end of a trunnion cap 24 and adapted, 90 when turned at right angles to the rod to overlie the cap, to securely lock the carriage in assembly. The caps and bearings may be formed with complementary ribs 25 and grooves 26 for an obvious purpose. 95

In assembling the gun the locking devices will be in the open position as shown in Figure 2, so that the top carriage may be hooked over the axle to support the trails therefrom. The gun with its cradle is then 100 mounted in the upper bearings, the trunnion caps are closed, and the levers may be grasped in either hand and simultaneously secured through a continuous movement.

In dismantling the gun the levers may 105 be rotated and pushed forwardly, the cradle

removed and the trails and top carriage lifted from the axle.

While in the foregoing there has been illustrated and described such combination and arrangement of elements as constitute the preferred embodiment of my invention, it is nevertheless desired to emphasize the fact that interpretation of the invention should only be conclusive when made in the light of the subjoined claims.

I claim:

1. In combination with a gun carriage, trails, a top carriage embodying a pair of spaced upright supports mounted on the front end of the trails, a vertical rib formed on each support and terminating in semi-circular bearings, the lower bearing adapted to hook over the axle, the upper bearing adapted to receive the cradle trunnions, a spacing bar for the supports, caps for the lower bearings pivotally mounted on either end of the spacing bar, a rod pivotally mounted on the free end of each cap, a lever eccentrically pivoted to the rod, caps for the upper bearings adapted to receive the levers whereby to lock the assembly, and means for permitting the top carriage to be traversed.

2. In combination with a gun carriage, trails, a top carriage embodying a pair of spaced upright supports mounted on the front end of the trails, a vertical rib formed on each support and terminating in semi-circular bearings, the lower bearing adapted to hook over the axle, the upper bearing adapted to receive the cradle trunnions, a spacing bar for the supports, caps for the lower bearings pivotally mounted on either end of the spacing bar, a rod pivotally mounted on the free end of each cap, a lever eccentrically pivoted to the rod, and caps for the upper bearings adapted to receive the levers whereby to lock the assembly.

3. In combination with a gun carriage, trails, a top carriage embodying a pair of spaced upright supports mounted on the front ends of the trails, a vertical rib formed on each support and terminating in semi-circular bearings, the lower bearing adapted to hook over the axle, the upper bearing adapted to receive the cradle trunnions, caps for the lower and upper bearings, a rod pivotally mounted on the free end of the lower caps, a lever eccentrically pivoted to each of the rods and adapted to cooperate with the upper caps to lock the assembly, and means for permitting the supports to be traversed in unison.

4. In combination with a gun carriage, trails, a top carriage embodying a pair of spaced upright supports mounted on the front ends of the trails, a vertical rib formed on each support and terminating in semi-circular bearings, the lower bearing

adapted to hook over the axle, the upper bearing adapted to receive the cradle trunnions, caps for the lower and upper bearings, a rod pivotally mounted on the free end of the lower caps, and a lever eccentrically pivoted to each of the rods and adapted to cooperate with the upper caps to lock the assembly.

5. In combination with a gun carriage, trails, a top carriage embodying a pair of upright supports mounted on the front end of the trails, each of said supports being formed with semi-circular bearing, the lower bearing adapted to hook over the axle, the upper bearing adapted to receive the cradle trunnions, pivotally mounted caps for the lower and upper bearings, a rod pivotally mounted on the free end of the lower caps, a lever eccentrically pivoted to each of the rods and adapted to cooperate with the upper caps to lock the assembly.

6. In combination with a gun carriage, trails, a top carriage embodying a pair of upright supports mounted on the front end of the trails, each of said supports formed with semi-circular bearings, the lower bearings adapted to hook over the axle, the upper bearing adapted to receive the cradle trunnions, caps for the lower and upper bearings, and a locking device pivotally mounted on each of the lower caps.

7. In combination with a gun carriage, a top carriage including means for supporting the carriage trails from the axle, means for receiving the cradle trunnions, and a pair of locking devices capable of continuous movement for simultaneously locking the top carriage to the axle and the trunnions to the top carriage.

8. In combination with a gun carriage, a top carriage including means for supporting the carriage trails from the axle, means for receiving the cradle trunnions, and locking devices for simultaneously locking the top carriage to the axle and the trunnions to the top carriage.

9. A top carriage for guns embodying a pair of upright supports, said supports formed with semi-circular lower and upper bearings, caps for closing the bearings, and means secured to the lower caps for locking both the lower and upper caps in position.

10. A top carriage for guns embodying a pair of connected upright supports, said supports formed with axle and trunnion bearings, caps therefor, means for locking the caps in position, and means for permitting the carriage to be traversed.

11. A top carriage for guns embodying axle supports and trunnion journals, caps for said supports and journals, and means for simultaneously locking such caps in place.

12. A top carriage for guns embodying axle supports and trunnion journals, caps

for the supports and journals, means for simultaneously locking such caps in place, and means on the supports and their caps cooperating with the axle to traverse the gun.

13. A top carriage for guns embodying a pair of upright supports adapted to rest on the gun carriage axle and receive the gun trunnions, means for locking the supports to the axle and to the trunnions, and a bar

connecting the supports and carrying said locking means.

14. A top carriage for guns embodying a pair of upright supports adapted to rest on the carriage axle and receive the gun trunnions, and combined locking means for securing each support to the axle and a trunnion.

HARRY C. ZIMMERMAN.
